UNITED STATES PATENT OFFICE.

LOUIS E. LAURENT, OF NEW YORK, N. Y., AND JAMES C. PATTERSON, OF EAST ORANGE, NEW JERSEY.

CONVEYING APPARATUS.

Application filed January 19, 1920. Serial No. 352,262.

To all whom it may concern:

Be it known that we, LOUIS E. LAURENT and JAMES C. PATTERSON, citizens of the United States, and residents, respectively, of New York, county of New York, State of New York, and East Orange, county of Essex, State of New Jersey, have invented new and useful Improvements in Conveying Apparatus, of which the following is a specification.

The invention relates to conveying apparatus which may be employed for any desired purpose within its range of work but which is particularly adapted for use in railroad building. Heretofore, in the building of railroads, where "fills" are to be made, it has been the usual practice to construct a track supporting trestle for the dumping cars which carry the filling material, which trestle subsequently becomes buried in the filling material and so lost for further use. This practice obviously is a very slow and expensive one on account of the time required in building the trestle and the cost of material and labor. It has therefore been an object of our invention to provide an apparatus by means of which railroad building may be accomplished much more expeditiously and economically than heretofore. This object is attained by an apparatus comprising as its main elements, an incline trestle mounted on wheels for movement along a railroad track and having a trackway thereon for dumping cars; a conveyer in sliding telescopic connection with said trestle for receiving the filling material from the dumping cars and discharging the same in advance of the trestle, the said trestle and conveyer being movable along the track one relatively to the other as the work advances; means in advance of the conveyer for holding the rails suspended in the plane of the road-bed preliminary to the filling in of the latter; and means, such as a laterally swinging chute, for receiving the material from the conveyer and discharging it in position to fill in the required width of the road-bed beneath the suspended rails.

Referring now to the accompanying drawings forming a part of this specification—

Fig. 1 is a side elevation of an apparatus embodying our invention in working position on a railroad track and showing the

conveyer extended in advance of the trestle substantially its full length.

Fig. 2 is a similar view showing the trestle advanced and the conveyer closed to substantially its shortest length.

Fig. 3 is a plan view of the apparatus showing the double and single trackway thereon, one merging into the other.

Fig. 4 is an enlarged cross-section taken through the line 4—4 of Fig. 1, and showing the endless conveyer belt broken away in order to more clearly show its supporting parts.

Fig. 5 is a side elevation of the parts shown in Fig. 4, on a like scale.

Fig. 6 is an enlarged cross-section of the trestle and conveyer, taken on the line 6—6 of Fig. 1, and showing diagrammatically a dumping car on one of the double tracks thereon.

Fig. 7 is an enlarged detail showing the terminal connection of one of the rails on a trailer connected with the trestle, and one of the railroad rails.

Fig. 8 is an end view of the same.

Fig. 9 is a side elevation of the front or rail laying end of the apparatus, showing a modified form of the filling material distributor.

Fig. 10 is a plan of the same.

Similar reference characters indicate like parts in the several figures of the drawings.

The movable trestle, indicated generally by A, may be of any suitable construction, the same preferably and as here shown being made up of open or skeleton frame work in usual manner. This trestle is mounted on wheels for movement along a surface track or railroad, and when adapted for work on a double track as here shown, is provided at its rear end with two pairs of flanged wheels 10, 10, and 11, 11, mounted respectively on axles 12 and 13, journaled in suitable bearings at the under side of the trestle frame. The two sets of rails forming the double track on which the trestle stands are indicated at 14 and 15, and as the distance between the centers of these tracks vary more or less, one of the said pairs of wheels, that indicated at 10, are rigidly attached to their supporting axle in order to hold the trestle laterally on the track, while the other pair, 11, are formed with double flanges for embracing the tracks and loosely mounted on

their supporting axle for endwise adjustment whereby they will automatically accommodate themselves to any variation between track centers.

5 As these two pairs of wheels at the rear end of the trestle are sufficient to steady the latter and hold it against lateral tilting, we preferably employ only one pair of wheels adjacent the forward end of the 10 trestle, as indicated on 10' and 11' in Fig. 4, both of which are double flanged and one, 10', being fixed to the axle, and the other, 11', being loose on the axle for endwise adjustment to any variation between tracks, as 15 described in connection with the adjustable rear wheels 11.

The trestle A is formed with an incline 20, terminating at its upper end in a lesser incline 21, at the dumping point. Supported on the incline 20 is a double track 22—23 which at its lower end is arranged in substantial alignment with the road or surface tracks and at its upper end merges into a single centrally arranged track 24, 25 whereby dumping cars, such as indicated at D, may be drawn up one track on the incline to a dumping position on the central track 24, and, after being emptied, be returned down the incline on the other track, 30 this switching of the car to the opposite track on the incline when returned as an "empty" being controlled by a suitable switch S. By having this double track and switch on the movable trestle, we avoid the 35 necessity of having a switch in the surface track which would have to be relocated from time to time as the apparatus is moved forward during progress of the work. The resulting saving in time and expense is obviously very substantial.

40 Coupled to the rear end of the trestle A is a trailer T, which is in the form of an incline mounted on wheels 26 and having rails 27 thereon in alignment with those of the trestle and those of the surface tracks, which rails terminate at their lower ends in tapered shoes or points 28, resting directly on the surface rails and having side flanges 29, 29, loosely embracing the latter, as shown 45 in Figs. 7 and 8. This trailer, which is loosely coupled to the trestle by any suitable means, such as the links 30, is for the purpose of shortening the trestle and adapting the same where it joins with the surface track to any irregularities in the latter.

50 Also, by reason of its trailing directly on the surface tracks, the necessity for breaking joints in the latter as the apparatus moves forward is avoided.

60 The filling material carried on to the trestle by the dumping cars, is discharged from the latter into a hopper H attached to the trestle below the upper central track 24, as best shown in Fig. 4, and is delivered 65 therefrom on to a conveyor C supported in

a position directly below the same, by which it is carried to a point in advance of the trestle where the road is being built. This conveyer, which may be of any suitable type, is here shown in the form of an endless belt 70 operating over end rollers 35, 35, and intermediate idlers 36, mounted on a suitable frame 37, which latter has a sliding telescopic connection with the trestle frame by resting on guides or rollers 38 therein, as 75 most clearly shown in Figs. 4 and 6. In connection with this endless conveyer we employ a belt tightener (not shown) such as is used in general practice.

The conveyer frame 37 at its front end 80 extends forward of the trestle and is mounted on flanged wheels 39 which rest and operate on the surface tracks like the front wheels 10' and 11' of the trestle, hereinbefore described. With this described arrangement of the trestle and conveyer, the latter, which is preferably made of considerable length, is gradually drawn forward through the trestle as the work progresses, until its rear end reaches a position adjacent to the 90 hopper H in the trestle, as shown in Fig. 1, at which time the trestle is advanced relatively to the conveyer and telescoping the same, as shown in Fig. 2. During such adjustment of the trestle relatively to the conveyer, the latter is of course held stationary by suitable fastening means, such, for instance, as clamping means (not shown) connecting it to the track. As the conveyer frame is advanced beyond the trestle, it is 100 adapted to be supported at proper intervals on the track by suitable means, such, for instance, as the wheels or rollers 65 shown in Fig. 1.

The conveyer at its front end is slightly 105 elevated as shown, in order to deliver the material carried thereby into a raised hopper H', which latter in turn discharges into a chute E, mounted for swinging movement in an arc across the line of the road, as indicated by the broken line in Fig. 3, for the proper distribution of the material. The hopper H' and chute E are both supported on the front end of the conveyer frame, the hopper being stationary and the chute being 110 carried by a vertical post 45 mounted for rotation in a step-bearing 46. In some instances where it may be desired to increase the radius of distribution beyond that for which the swinging chute E is adapted, we 115 may provide a supplemental conveyer of the desired length, such as indicated at C' in Figs. 9 and 10, which will be of the same or similar type as that of the main conveyer. This supplemental conveyer may be supported in any suitable or usual manner, the same as here shown being connected at its inner end with the conveyer frame and at its outer end with a swinging boom 47, which latter is supported by suitable rigging R.

120 125 130

In the use of the apparatus, the conveyer C will be operated from a suitable power plant, here shown as an engine P mounted on a platform 48 at the front end of the 5 conveyer frame. This may be accomplished by a driving belt 49 connecting the engine drum with the adjacent conveyer pulley 35 as shown. Where the supplemental conveyer is used, this may be similarly operated 10 from the engine drum through a belt 50.

The dumping cars will also be operated from the same power plant by means of a hauling rope 55 winding on a drum 56 driven by the engine through a belt 57. 15 This hauling rope will have a hook or like means for detachable connection with the car so that as one car is hauled up the incline and subsequently lowered as an empty, the rope may be disconnected therefrom 20 and connected to a filled car on the opposite track. Also, when the trestle is to be advanced in its telescopic connection with the conveyer, as from the position shown in Fig. 1 to that shown in Fig. 2, the same 25 engine will be utilized for this by simply connecting the hauling rope with the trestle at some convenient point thereon. When the conveyer is to be advanced, this also may be accomplished by the engine P 30 through the medium of a rope and tackle (not shown) connecting with some stationary object in usual manner.

Carried on the front end of the conveyer frame are suitable booms and rigging for 35 laying tracks in advance of the apparatus as the filling in of the road-bed progresses. A block and tackle M carried by a boom 60 is utilized to hoist a rail, as 61, after which a loose rope 62 running through a block 40 63 on the boom 60, is fastened to the end of the rail. The latter is then located in the plane of the road-bed with one end resting on a tie and its opposite end suspended over the space to be filled, as shown in Fig. 1, 45 after which the rope 62 is tightened to support the end of the rail and the block and tackle M is disconnected therefrom, as shown in Fig. 2. A clear space is now provided for the operation of the chute or 50 supplemental conveyer in distributing the filling material. After the fill has been completed to the end of the rails or some distance in advance thereof, ties are placed beneath the said rails, after which the conveyer is again advanced the desired distance 55 for continuing the work. In this way we are enabled to completely build the road in advance of the apparatus and then advance the latter over such road as the work progresses.

What we claim is:

1. A conveying apparatus, comprising a movable elongated trestle having a track-way for dumping cars, a hopper carried by 60 the trestle in position for receiving material

from said cars, and a bodily movable conveyer in longitudinal telescopic connection with said trestle for receiving the material from the hopper, whereby the conveyer may be extended outwardly from said trestle 70 or said trestle may be moved up over said conveyer without interfering with the unloading and conveying operations.

2. A conveying apparatus, comprising a movable elongated trestle having a track-way for dumping cars, and a bodily movable conveyer mounted within said trestle in longitudinal telescopic connection with said trestle for receiving the material delivered 75 from said cars, whereby the conveyer may be extended outwardly from said trestle or said trestle may be moved up over said conveyer without interfering with the unloading and conveying operations.

3. A conveying apparatus, comprising a 80 movable elongated trestle having a track-way for dumping cars and conveyer-supporting-means below said trackway and in line therewith, and a conveyer slidably mounted on said conveyer supporting means 85 in longitudinal telescopic connection with the trestle for receiving material delivered from said cars.

4. A conveying apparatus, comprising a 90 movable elongated trestle having a track-way for dumping cars and conveyer supporting means below said trackway and in line therewith, a conveyer slidably mounted on said conveyer supporting means in longitudinal telescopic connection with the 95 trestle, and a hopper carried by the trestle in position for receiving material from the cars and delivering the same to the conveyer in any of the adjusted positions.

5. A conveying apparatus, comprising an 100 inclined elongated trestle mounted on wheels for movement along a railroad and being provided with tracks to receive wheeled dumping cars thereon, an incline trailer connected with said trestle and having tracks joining those of the trestle with those of the railroad, and a bodily movable conveyer in longitudinal telescopic connection with the trestle for receiving material 105 delivered from the dumping cars thereon in 110 any of the relative adjusted positions of the trestle and conveyer.

6. A conveying apparatus, comprising an 115 inclined elongated trestle mounted on wheels for movement along a railroad and being provided with tracks to receive wheeled dumping cars thereon, an incline trailer loosely connected with said trestle and having tracks joining those of the trestle with those of the railroad, the said trailer tracks 120 having means for maintaining the same against lateral displacement on the railroad rails, and a bodily movable conveyer in longitudinal telescopic connection with the trestle for receiving material delivered from 125 130

the dumping cars thereon in any of the relative adjusted positions of the trestle and conveyer.

7. A conveying apparatus, comprising an elongated trestle mounted on wheels for movement along a railroad and being provided with a trackway thereon for dumping cars, said trackway including a double track and a single track into which the double track merges, a bodily movable conveyer in longitudinal telescopic connection with the trestle and arranged with a part thereon beneath said single track for receiving material delivered from the cars, and a switch in the said trackway for permitting cars to pass on to the trestle over one track and leave by the other.

8. A conveying apparatus, comprising a movable trestle mounted on wheels for movement along a railroad and being formed with an inclined portion terminating at the top of the trestle in a lesser incline, a trackway on said trestle for dumping cars including a double track merging into a single track, a hopper carried by the trestle below the single track for receiving material from the cars thereon, a conveyer in telescopic connection with the trestle for receiving the material from said hopper, and a switch in the said trackway on the trestle for permitting the cars to pass on to the trestle over one track and leave by the other.

9. A conveying apparatus, comprising a movable trestle mounted on wheels for movement along a railroad and being provided with a trackway thereon for dumping cars, a conveyer frame in sliding telescopic connection with said trestle having one end extended in advance of the latter and mounted on wheels for movement along the railroad, a conveyer mounted on said conveyer frame, and means for moving the trestle and conveyer frame along the railroad one relatively to the other.

10. A conveying apparatus, comprising a movable trestle mounted on wheels for movement along a railroad and being provided with a trackway thereon for dumping cars, a conveyer frame in sliding telescopic connection with said trestle having one end extended in advance of the latter and mounted on wheels for movement along the railroad, a conveyer mounted on said conveyer frame, and means on the conveyer frame for advancing the trestle relatively to the conveyer.

11. A conveying apparatus, comprising a movable elongated trestle having a trackway for dumping cars a bodily movable conveyer in longitudinal telescopic connection with said trestle for receiving the material delivered from said cars, and a supplemental conveyer arranged to receive material

from the main conveyer and being pivotally mounted for lateral movement in distributing the material received by it.

12. A conveying apparatus, comprising a movable elongated trestle having a trackway for dumping cars, a bodily movable conveyer in longitudinal telescopic connection with said trestle for receiving the material delivered from said cars and a supplemental conveyer arranged to receive material from the main conveyer and being pivotally mounted for lateral movement in distributing the material received by it, both of said conveyers being in the form of endless carriers, and operating means for said conveyers.

13. A conveying apparatus, comprising a movable trestle having two sets of supporting wheels for movement along a double track, one set of wheels being laterally adjustable relatively to the other set, a trackway on the trestle for dumping cars, and a conveyer in sliding telescopic connection with the trestle for receiving material delivered from said cars.

14. A conveying apparatus, comprising a movable trestle having two sets of supporting wheels for movement along a double track, one set of wheels being laterally adjustable relatively to each other and to the other set, a trackway on the trestle for dumping cars comprising a single track, a double track merging into said single track, and a switch, and a conveyer in sliding telescopic connection with the trestle at a point below the single track for receiving material delivered from said cars.

15. An apparatus for railroad building, comprising a movable trestle mounted on wheels for movement along a railroad and being provided with a trackway thereon for dumping cars, a conveyer frame in sliding telescopic connection with said trestle having one end extended in advance of the latter and mounted on wheels for movement along the railroad, a conveyer mounted on said conveyer frame, means for suspending rails in advance of the conveyer and in the plane of the road-bed, and means for discharging the material from the conveyer beneath said suspended rails.

16. An apparatus for railroad building, comprising a movable trestle mounted on wheels for movement along a railroad and being provided with a trackway thereon for dumping cars, a conveyer frame in sliding telescopic connection with said trestle having one end extended in advance of the latter and mounted on wheels for movement along the railroad, a conveyer mounted on said conveyer frame, means mounted on the conveyer frame and movable therewith for suspending rails in advance of the conveyer and in the plane of the road-bed, and

a supplemental conveyer pivotally mounted on the conveyer frame for movement in an arc extending across the road-bed and being adapted to receive the material from the 5 main conveyer and discharge the same beneath said suspended rails.

17. A conveying apparatus, comprising a movable elongated trestle adapted to receive unloading vehicles, and a bodily movable conveyer in longitudinal telescopic connection with said trestle for receiving the 10

material unloaded from said vehicles, whereby the conveyer may be extended outwardly from said trestle or said trestle may be moved up over said conveyor without interfering with the unloading and conveying operations. 15

Signed at New York, in the county of New York and State of New York, this 8th day of January 1920.

LOUIS E. LAURENT.

JAMES C. PATTERSON.
